United States Patent Office.

E. L. GAYLORD, OF TERRYVILLE, CONNECTICUT.

Letters Patent No. 68,496, dated September 3, 1867.

IMPROVEMENT IN PIANO-LOCKS.

The Schedule referred to in these Letters Patent and making part of the same.

TO ALL WHOM IT MAY CONCERN:

Be it known that I, E. L. GAYLORD, of Terryville, in the county of Litchfield, and State of Connecticut, have invented a new and improved Lock, and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved lock, of that class which is designed for piano-fortes, sewing-machine cases, and other articles which have hinged lids or covers.

The invention consists in the mechanism employed for operating the bolts, two being employed and arranged to move or work in the arc of one or more circles. In the accompanying sheet of drawings—

Figure 1 is an internal view of my improved lock.

Figure 2, a section of the same taken in the line *z z*, fig. 1.

Similar letters of reference indicate like parts.

A represents the case of the lock, which may be constructed in the usual or in any proper manner. Within the lock-case there is fitted a slide, B, so arranged as to be raised and lowered by a key, C, of any proper construction. This slide may be fitted on any suitable guide or stump, *a*, to keep it in place, and it may be moved or operated by an arm, *b*, projecting from an arbor, *c*, in which the key is fitted; said arm having a pin, *d*, at its outer end to pass into an oblong slot, *e*, in the slide, as shown clearly in fig. 1. I do not, however, confine myself to this plan, as other means may be employed. A spring, *D*, bears against one side of the slide B to keep it in place when both in an elevated and depressed state. E E are the bolts, the outer parts *e* of which are of curved form, being portions of circles; the other parts *f* are straight and nearly at right angles with *e*, the inner ends of *f* being pivoted within the case, as shown at *g g*. The parts *f* of the bolts have pins *h* projecting from them, one from each, and these pins are fitted in oblong slots *i* in the slide B, and hence it will be seen that by throwing up the slide B the curved parts *e* of the bolts will be shoved up out of the lock-case and through holes in the usual plate F, which is generally attached to the lid; said parts *e* moving in the paths of circles, of which the pivots *g g* are the centres, and when the slide B is drawn down the parts *e* will be drawn down within the lock-case or out from the holes in the plate F. If necessary or desired both of the bolts E may work on one and the same pivot *g*.

Having thus described my invention, I claim as new, and desire to secure by Letters Patent—

The two bolts E E, working on separate or on a common centre or pivot, *g*, in combination with a vertically-moving slide, B, connected with the bolts, and all arranged substantially as shown and described.

The above specification of my invention signed by me this 16th day of April, 1867.

E. L. GAYLORD.
